RECEPTACLE FOR FILEING PAPERS

John Podgursky, Brooklyn, N. Y.

Application July 26, 1949, Serial No. 106,777

3 Claims. (Cl. 229—77)

1

This invention relates to an article providing a receptacle for filing papers or other contents. The improved article forms a combination file folder, mailing envelope and carrying case or portfolio.

The present invention primarily concerns an improvement in the known basic type of office file folder of the character formed of a centerfolded, four-sided blank of manila paper that in folded condition provides a receptacle for filing papers. Such a receptacle in folded condition has a closed side defined by the centerfold and three normally open sides. The file folder or receptacle may further include openings therein in the marginal area thereof accommodating the use of a metal fastener of known character adapted to secure the papers or contents for the folder to one or both of the hinged parts of the folder. The receptacle may also include a tab protruding from one of its parts that may be labeled to identify the contents of the folder. Folders of the described character are constructed in different sizes to accommodate correspondingly proportioned paper sheets.

The improved article while usable as a file folder of the character noted includes features that adapt the receptacle for further use as a mailing envelope or as a carrying case in which the open sides of the folder are interlocked. While the described well-known type of folder is made of manila paper, the improved article may be constructed of any similar or equivalent material having the desired thickness and stiffness.

One of the features of the present invention is in the provision of an article of the character described having two flat hingedly connected parts or covers that includes a fastening member on one of the parts for each of the open sides thereof and a corresponding engaging element on the other of the parts adapted to fit each of the fastening members. When in connected condition the fastening members and engaging elements interlock the open sides of the receptacle so that the same is usable as a portfolio.

A further feature of the invention is in the provision of a folder of the character described in which parallel tabs are fixed to one of the parts or covers of the article providing slots to receive the top and bottom edges of the paper to be filed in the folder thus obviating the need for use of metal fasteners with the folder.

Other features and structural details of the invention will be apparent from the following description when read in connection with the accompanying drawings, wherein:

2

Fig. 1 is a plan view of an unfolded blank embodying the features of the present invention.

Fig. 2 is a perspective view of the article shown in Fig. 1 illustrating the same in a partially folded condition.

Fig. 3 is a perspective view of the article shown in Fig. 1 with the same in one of its possible interlocked conditions.

Fig. 4 is a view similar to Fig. 3 showing the other possible interlocked condition of the article illustrated in Fig. 1.

Fig. 5 is a view similar to Fig. 1 showing a modified form of the invention.

Fig. 6 is a view similar to Fig. 2 for the form 15 of the invention shown in Fig. 5.

Fig. 7 is a perspective view showing the article illustrated in Fig. 5 in interlocked condition.

Fig. 8 is a view similar to Figs. 1 and 5 showing a third embodiment of the invention.

Fig. 9 is a view similar to Figs. 2 and 6 showing the article illustrated in Fig. 8 in a partially interlocked condition.

Figs. 10 and 11 are respective back and front perspective views showing the article illustrated in Fig. 8 in an interlocked condition, and

Fig. 12 is a view similar to Fig. 9 showing a different method of connecting the parts of the article shown in Fig. 8.

With particular reference to Figs. 1 to 4 inclusive, the improved article is shown as formed of a four-sided blank having centerfold-connected parts of substantially equal size. As shown, one of the parts may be provided by a straight-sided flat front cover 20. The other of the parts may be a back cover 21 of substantially the same shape and size as the front cover 20. The hinged connection for the covers or the centerfold is indicated at 22. In a folded condition, the hinge or centerfold between the parts provides a common side or end that is closed. With the form of blank illustrated, the known type of folder has three normally open sides or ends when in folded condition, one at the top, one at the bottom, and one at the side opposite the centerfold. As shown, the blank may be provided with a number of slots 23 in the marginal area thereof in both covers 20 and 21, for the purpose of accommodating a metal fastener of known character such as designated at 24 adapted to secure the papers or other contents (not shown) for the folder in position against the inner surface of the covers.

In accordance with the present invention, a fastening member in the form of an overlying tab is provided on the marginal area of one of the parts or covers for each of the normally open

sides of the folder. A corresponding element is also provided on the marginal area of the other of the parts or covers that is received by each of the fastening members. With the members and elements in fitted condition, the open sides of the article are interlocked. As shown in Fig. 1, the fastening members of the folder may be a number of tabs formed on a portion of an insert 25 secured on the marginal inside surface of the cover 21. The insert 25 may be of the same material as the cover and the parts may be secured by a glue connection at the edge of the marginal areas thereof. The slots 23 accommodating the metal fasteners extend through both the cover 21 and the insert 25. The fastening tabs in this form of the invention are indicated at 26, 27, 28, 29 and 30 all of which are provided by the insert 25. Tab members 26 and 30 with the cover 21 provide engaging slots along the top and bottom sides of the folder shown in Fig. 1. Tab members 27, 28 and 29 provide one element of the fitting adapted to interlock the side of the receptacle or folder opposite the centerfold 22.

The corresponding fitting portion in the other of the parts or cover 20, in this instance, for the tab or fastening member 28 is provided by a slot 31. In making this connection, the parts are folded as indicated in Fig. 2 and tab 28 is bent upwardly for insertion in the slot 31. Figs. 30 3 and 4 show a connected fitting of the tab 28 and the slot 31.

In this form of the invention, the fitting portion on the other of the parts or cover 20, in this instance, for the slots provided by the top and bottom tabs 26 and 30 respectively include the marginal surface of one of the sides of the part and an inturned flap part designated at 32 and 33. The top inturn part 32 is provided by scoring or break lines 34, 35 in the cover 20 along which the material is broken before the fold is made and a folding line 36 to which the scoring lines extend. Line 36 is parallel to the edge of the cover and the scoring lines may extend from the corners of the cover 20 as shown so that the infold is trapezoidal in shape. Flap 33 at the bottom of the cover is similarly formed by scoring lines 37, 38 and fold line 39. Fig. 2 shows the flaps 32 and 33 in an inturned condition. Fig. 4 shows flaps 32, 33 and the marginal surface of the cover in a fitted position in the slots provided by the respective tab members 26 and 30, the tabs 29 and 30 overlying the respective inturned flaps 32 and 33. The fitting portion for the tabs 27, 29 on the insert 25, is provided in this form of the invention by the triangular end tabs 40, 41 of the respective inturn flap parts 32 and 33. Tabs 40, 41 are inserted under the tabs 27 and 29, respectively as clearly shown in Fig. 2.

To facilitate use of the receptacle as a mailing envelope, the inner edge 42 of cover 20 may contain a glued surface as indicated. A portion of the undersurface of tabs 26, 27, 28, 29 and 30 may also contain a glued surface. When used as a portfolio or carrying case, the parts may be folded and interfitted as shown in Fig. 3 of the drawing. Here the gluing connections are not made and flaps 32 and 33 lie over the respective tab portions 26 and 30. The envelope is interlocked by the fastening tabs 27, 29 and 28 and the respective interfitted portions 40, 41 and the slot 31, in this instance.

The parallel slots defined by tabs 26 and 30 of the insert 25 and the cover 21 obviate the

need for the use of the fasteners 24 to secure the papers or other contents within the receptacle. The contents are then secured between the parallel top and bottom tabs 26 and 30 and the cover 21, the top edge of the contents fitting in the slot at the top of the receptacle and the bottom edge of the contents fitting in the slot at the bottom of the receptacle. The position of a piece of paper secured in the receptacle by the tabs 26, 30 is indicated by the dotted lines in Fig. 1.

Figs. 5, 6 and 7 show a modification of the invention in which the receptacle is particularly adapted for use as a carrying case or portfolio. As shown, the back cover is designated at 45, the front cover at 46, the centerfold at 22 and the tab fitting inturned flaps at 52 and 53. In this form of the invention, the fastening members or tabs 48, 49 and 50 are provided by arcuate openings or slots in the respective top, side and bottom marginal surfaces of the cover 45. Protruding tab 51 from cover 45 may be labeled to identify the contents of the folder. In this form of the invention, the triangular end portions 54, 54' and 55, 55' on flaps 52 and 53 provide tab or fastening members and the corresponding fitting portions therefor as indicated in Fig. 6 are slot 56 for tab 54, slot 57 for tab 54', slot 58 for tab 55 and slot 59 for tab 55'. Slot 60 in cover 46 is provided to engage the tab 49. The inturned flaps 52 and 53 and the adjacent marginal surfaces of the cover 46 underlie the respective tabs 48 and 50 as clearly shown in Fig. 7 when the receptacle is in interlocked condition.

In the form of the invention shown in Figs. 8 to 12 inclusive, the back cover is designated at 62, the front cover at 63 and the centerfold at 64. The fitting provided by tab 49 and slot 61 is similar to that shown in Fig. 1. In this construction, the tab fastening members include two flaps 65 and 66 respectively hinged at 68 and 67 at the opposite edges of the cover part 63. The slots 23 for the fastener 24 may be provided in the flap 65 so that the papers or contents are hinged connected to the receptacle. In ordinary use the bottom flap 66 may provide a marker for use with the papers. Slots 69 may be provided in flap 65 to receive the end of flap 66. Slots 70 may be provided in the flap 66 to receive the end of flap 65. The receptacle may be interlocked in two different ways one of which is shown in Figs. 9, 10 and 11. With this method of interlocking the receptacle, the flaps 65 and 66 extend around the outside of the cover 62, being bent as shown in Fig. 9 and inserted through the parallel slots 71 and 72 in the cover 62. The end of the outer flap 65 threaded through slots 71, 72 engages in the slits 79 provided in flap 66. As shown in Fig. 12, a similar connection may be made between the parts with the flaps 65, 66 threading the slots 71, 72 from the inside of the cover 62. In this arrangement the connection between the flaps 65, 66 is made within the cover 62 instead of outside of the same.

Since many changes could be made in the above construction and many apparently widely different embodiments of this invention could be made without departure from the scope thereof, it is intended that all matter contained in the above description or shown in the accompanying drawings shall be interpreted as illustrative and not in a limiting sense.

I claim:

1. An article of the class described consisting of a four sided blank having centerfold connected

flat parts of substantially corresponding size and shape that fold together with a common straight closed end and three straight normally open ends, a fold line on one of said parts perpendicular to the closed common end of the article and break lines connecting the ends of the fold line and one of the edges of the part, said fold and break lines providing a flap in one of the marginal areas of said part, and a tab situated on a juxtaposed marginal area of the other of said parts overlying the inturned flap in the first part to interlock the parts at one of the normally open ends of the article adjacent the common closed end.

2. An article of the class described consisting of a four sided blank having centerfold connected flat parts of substantially corresponding size and shape that fold together with a common straight closed end and three straight normally open ends, a fold line on one of said parts perpendicular to the closed common end of the article and break lines connecting the ends of the fold line and one of the edges of the part, said fold and break lines providing a flap having a tab end portion in one of the marginal areas of said part, and a second tab situated on a juxtaposed marginal area of the other of said parts overlying the tab end portion on the first part with the flap in inturned condition to interlock the parts at one of the normally open ends of the article.

3. An article of the class described consisting of a four sided blank having centerfold connected flat parts of substantially corresponding size and shape that fold together with a common straight closed end and three straight normally open ends, a fold line on one of said parts perpendicular to

5 the closed common end of the article and break lines connecting the ends of the fold line and one of the edges of the part, said fold and break lines providing a flap having a tab end portion in one of the marginal areas of said part, a second tab situated on a juxtaposed marginal area of the other of said parts overlying the tab end portion in the first part with the flap in inturned condition to interlock the parts at one of the normally open ends of the article adjacent the common closed end, and a third tab situated on a juxtaposed marginal area of the other of said parts also overlying the inturned flap in the first part to further interlock the parts at the same normally open end of the article.

10 15 20 25 30 35 JOHN PODGURSKY.
